(57) **CLAIM**

The ornamental design for a cup, as shown and described.

DESCRIPTION

FIG. 1 is a top, front perspective view of a cup, showing our design;

FIG. 2 is a bottom, front perspective view thereof;

FIG. 3 is a front elevational view thereof, where the rear elevational view is identical thereto;

FIG. 4 is a right side elevational view thereof, where the left side elevational view is identical thereto;

FIG. 5 is a top plan view thereof; and,

FIG. 6 is a bottom plan view thereof.

The features shown in phantom lines in the figures are shown for illustrative purposes only and form no part of the claimed design.
